UNITED STATES PATENT OFFICE.

BAXTER M. ASLAKSON, OF SALEM, OHIO.

IGNITION DEVICE.

949,138.

Specification of Letters Patent. Patented Feb. 15, 1910.

Application filed January 14, 1908. Serial No. 410,730.

To all whom it may concern:

Be it known that I, BAXTER M. ASLAKSON, a citizen of the United States, and resident of Salem, in the county of Columbiana and State of Ohio, have invented certain new and useful Improvements in Ignition Devices, of which the following is a specification.

My invention relates to mechanical spark plugs and has for its object the production of a device of the character referred to, of simple and durable construction, in which the same electric current which serves to generate the spark when broken, also operates the device mechanically to establish the spark gap when the circuit is closed.

A further object is to provide a powerful magnet of laminated and iron clad construction which is comparatively inexpensive and highly compact.

In the accompanying drawings forming part of this specification.—Figure 1, is a front elevational view of the novel spark plug. Fig. 2, is a side view of the same. Fig. 3, is a plan view, partly in section, disclosing the construction of the magnet and armature parts.

My device is preferably operated in connection with a timer, by means of which an electric circuit is established at the proper instant to effect the operation of the device, the breaking of said circuit causing a spark to be formed between the contact points of the device located within the cylinder of a gas engine, to ignite the gas therein.

A, indicates a casting usually made of cast iron, having a flange portion A', provided with holes through which bolts are passed to secure it to the cylinder of an engine, the body portion A², constituting a plug fitting into an opening in the engine cylinder. Extending through the casting A, is a metal rod B, provided with a shoulder B', which abuts the face of the casting A and serves to effect a tight joint at this place. The rod B, is provided at one end with an angular projection B², in which is fitted a contact pin C, adapted to contact with one end of the rod D, also extending through the casting A, but which is insulated therefrom by a tube of insulating material such as mica, indicated in dotted lines designated E, and by two insulating washers F and G, respectively, and is held in position by a nut H, which also coacts to present a binding post

to hold one end of a wire I, in contact with the rod D, two metal washers J and K, being located on each side of said wire and in contact with the rod D, to effect a good electrical contact. Connected to the upper end of rod B, is a collar L, which is held in position by a pin M, and formed integral with said collar is a projection L', containing a hole in its under side in which one end 65 of a helical spring N, is held, said spring extending around said collar and with its lower end engaged within a small hole in the top of the casting A, the spring serving to hold the rod B, so that the contact C will 70 normally rest against a contact area on the rod D.

Bolts O, O, rigidly connected to the flange portion A', pass through the bend P', of a magnet core P, and through section Q, Q, 75 at either side of said bend, the threaded projecting ends of the bolts being engaged by nuts O', O', serving to firmly clamp the electro-magnet R, to the casting A. The core P, is composed of a series of laminated 80 sections which are held together both by the bolts O, O, and by pins S, S, the latter containing intermediately located threaded sockets for the engagement of the ends of screws T, T, projecting to constitute guides for an 85 armature U, the screw heads acting as stops to limit the movement of the armature from the core poles.

Centrally secured to the armature by a nut V', is the threaded end of a rod V, 90 which extends slidably within a tube of insulating material W, disposed between the magnet coils, and having its forward threaded portion clamped to the core bend P', by nuts W', W², the rod V, extending beyond 95 the projecting end of the tube.

A coiled expansion spring X, embraces the tube between the coils and abuts at one end against the inner tube-fastening nut W', while its outer end bears against the 100 armature to normally maintain the latter repelled relative to the magnet poles.

The ends of the wire forming the magnetic coils, are connected with binding posts X', X², respectively, the post X², being connected by the short length I, of wire clamped between the plates J, K, at the end of the rod D.

The positive conductor leading from a timer on the engine, is connected to the 110 binding post X², and the return conductor is connected to the negative pole of the

2

timer at one end and grounded at some suitable point on the engine, a battery or other source of electric current being included in the circuit. Therefore, when the timer contacts close the circuit, the current flows to the binding post X^2 , through the electro-magnet coils to the binding post X' , conductor I, rod D, and contact C and through the rod B, to the grounded terminal. The completion of the circuit thus described, energizes the magnet which attracts the armature U, thereby causing the rod V, to exert a thrust against the projection L', at one side thereof, with sufficient force to turn the rod B, and move the contact C, from contact with the rod D, thus suddenly breaking the circuit and causing a spark to be generated. It will be understood that the armature will vibrate rapidly and continuously so long as the timer is in position to close the circuit, and therefore more than one spark may be generated to cause the ignition of the gases in the cylinder.

The use of the laminated core in the present construction of electro-magnets permits of quick magnetic action between the armature and the poles.

An ignition device embodying my invention is not only of simple and durable construction, but is capable of high efficiency of operation.

Having thus described my invention, what I claim as new and desire to secure by Letters Patent, is—

35 1. The combination in a sparking device, of rods supported in bearings insulated with respect to each other, one of said rods being revoluble and normally maintained in contact at one end with the other rod, a projection on said revoluble rod, and electro-magnetic means comprising coils, a yoke-shaped core, an armature and a rod connected thereto which extends between the coils, and is adapted to exert a thrust against 40 the rod projection to turn its rod and interrupt its contact with the other rod.

45 2. The combination in a sparking device,

of a casting, rods bearing therein but insulated with respect to each other, one of said rods being revoluble and normally maintained in contact at one end with the other rod, electro-magnetic means comprising coils, a laminated yoke-shaped core and an armature with means extending between the coils for acting on the revoluble rod to 55 turn the same and interrupt its contact with the other rod, the bend of the yoke-shaped core being bolted to the casting.

3. The combination in a sparking device, of a casting, rods bearing therein but insulated with respect to each other, one of said rods being revoluble and normally maintained in contact at one end with the other rod, electro-magnetic means comprising coils, a laminated yoke-shaped core and an 60 armature with means located between the coils comprising a rod for acting on the revoluble rod to turn the same and interrupt its contact with the other rod, said electro-magnetic means being secured to the 65 casting by bolts projecting therefrom, passing through the bend of the core and engaged by clamp nuts.

4. The combination in a sparking device, of a casting, rods bearing therein but insulated with respect to each other, one of said rods being revoluble and normally maintained at one end in contact with the other rod, electro-magnetic means comprising coils, a laminated yoke-shaped core, the latter being secured to the casting, pins securing the laminations, screws bearing in said pins, an armature guidingly supported on said screws and means coactive with the armature for turning the revoluble rod to 70 interrupt its contact with the other rod.

Signed at New York in the county of New York and State of New York this tenth day of January A. D. 1908.

BAXTER M. ASLAKSON.
